(57) **CLAIM**

The ornamental design for a digital microscope, as shown and described.

DESCRIPTION

FIG. 1 is a front, right, top perspective view of a digital microscope, showing my new design;

FIG. 2 is a rear, left, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is a front, right, top perspective view of the digital microscope in a detached state;

FIG. 10 is a rear, left, bottom perspective view of the digital microscope in a detached state; and,

FIG. 11 is an enlarged view of detail 11 in FIG. 9.

The dashed broken lines in the figures illustrate portions of the digital microscope that form no part of the claimed design.

The dash-dot-dash broken lines are for notating enlarged views and form no part of the claimed design.
